HYDRAULIC SWIVEL HAVING IMPROVED
MUD JOINT

Guglielmo R. Tremolada, Los Angeles, Calif., assignor to Emsco Derrick & Equipment Company, Los Angeles, Calif., a corporation of California

Application March 27, 1940, Serial No. 326,259

14 Claims. (Cl. 255—25)

My invention relates to swivels such as used in the rotary drilling of wells, and relates in particular to a swivel wherein the load of a string of drill pipe is carried on a body of oil interposed between a piston and the end wall of a cylinder in which the piston operates.

In the preferred form of device on which my present invention is an improvement, a cylinder is equipped so that it may be suspended in vertical position from the hoisting equipment of a derrick. In this cylinder there is a rotatable and axially movable piston having a piston rod which extends downward through a packed opening in the lower end wall of the cylinder, the piston having a travelling guide to maintain it in coaxial relation to the cylinder and being supported on a body of hydraulic fluid, substantially as set forth in detail in my copending application Serial No. 230,747, filed September 19, 1938, for improved hydraulic expanding swivel. It is an object of my present invention to provide a hydraulic swivel of the general character set forth hereinabove wherein a swivelled fluid connection is applied to the upper portion of the drilling string for delivering into the drilling string a suitable drilling fluid, such as rotary mud or water, and wherein the swivelled fluid connection and the cylinder of the device are connected for relative axial movement and in such manner that there will be no relative rotation of the swivelled fluid connection and the cylinder of the hydraulic device.

A further object of the invention is to provide a rotary swivel having thrust bearing means for supporting the load of a drilling string and having a swivelled fluid connection, hereinafter referred to as mud joint, both of which parts are cooled during their operation by inter-connected cooling means.

It is a further object of the invention to provide a rotary swivel having means for permitting a downward feeding movement of the drilling string and a mud joint connected to the drilling string below the rotary swivel, with extensible means extending from the mud joint to the body or shell of the rotary swivel so as to permit relative axial movement of the mud joint and the shell of the swivel, such extensible interconnecting means having fluid passages through which a cooling medium may be circulated between the rotary swivel and the mud joint.

It is a further object of the invention to provide a rotary swivel and associated mud joint wherein the mud joint has cooling chambers to

receive a cooling medium such as water and upwardly extending tubes which have sliding engagement with the shell of the hydraulic swivel so as to communicate with a cooling chamber in which a fluid cooling medium is circulated to cool the operating parts of the rotary swivel.

Further objects and advantages of the invention will be brought out in the following part of the specification.

Referring to the drawings which are for illustrative purposes only:

Fig. 1 is a sectional view of a preferred form of my invention.

Fig. 2 is a side view of Fig. 1 partly sectioned on the plane 2—2 of Fig. 1.

Fig. 3 is an enlarged fragmentary section taken as indicated by the line 3—3 of Fig. 1.

Fig. 4 is a cross-section to enlarged scale taken as indicated by the line 4—4 of Fig. 1.

Fig. 5 is a cross-section taken as indicated by the line 5—5 of Fig. 3.

As shown in the drawings, the assembly includes a rotary swivel 10 having a bail 11 at its upper end whereby it may be connected to a suitable suspension means, such as a travelling block in a derrick, and a mud joint 12 disposed in a position between the rotary swivel 10 and the upper end of a kelly bar 13 constituting the upper extremity of a string of drill pipe.

30. The rotary swivel comprises a cylinder 14 having therein a thrust bearing means in the form of a piston 15 which is secured to a piston rod 16. The rod 16 projects down through a coaxial opening 17 in a lower end wall 18 for the cylinder, this end wall 18 cooperating with the piston 15 to form a chamber 19 in which a body of hydraulic fluid, such as oil, may be confined. the upper surface of such body of hydraulic fluid engaging and supporting the piston 15 and accordingly forming a lower bearing element to take the downward thrust of the piston 15 which serves as the upper bearing element. The end wall 18 is secured to the lower end of the cylinder 14 by use of stud bolts 20, and has an upwardly projecting hub 21 surrounding a portion of the opening 17, this hub 21 carrying a coaxial sleeve bearing 22 in which the rod 16 may rotate and through which it may slide as the elevation of the piston 15 changes. Below

45. the bearing 22 a packing counterbore 23 is provided for a suitable packing means 24 which is held in place by means of a gland 25, a cup 26 being placed below the gland 25 to catch any oil leakage which may pass downward around the shaft and having a spigot 27 whereby the ac-

cumulated oil may be periodically drained. A piston guide 28 is associated with the piston so as to move axially therewith in the cylinder 14, this piston guide 28 being mounted on the portion 29 of the rod 16 which projects above the piston 15, by means of roller bearings 30.

Near the upper end of the cylinder 14, such as below the laterally projecting trunnions 31 which engage the bail 11, there is a radial flange 32, and at the lower end of the cylinder 14 there is a radial flange 33 to which the lower end wall 18 is bolted. A tubular shell 34 comprising a plate rolled to cylindrical form is placed around the cylinder 14 and is connected to the flanges 32 and 33 in fluid tight relation, as by welding for example, so as to form around the cylinder 14 a chamber for circulation of a temperature stabilizing or cooling medium which is ordinarily water. Openings are extended through the flange 33 in directions parallel to the axis of the rod 16, through which openings 36 tubular conduit members 37 may slide. The openings 36 are preferably placed on diametrically opposite sides of the flange 33 and tubular guide members 38 are secured in alignment with the openings 36 in downwardly projecting position, by means of cap screws 39 which pass through flanges formed at the upper ends of the members 38. Packing chambers 40 are formed around the tubular member 37 preferably in the plane of joinder of the guide members 38 with the lower end wall 18.

The mud joint 12 comprises a cylindrical body 41 having threaded connection through use of a coupling sleeve 42 with the lower end of the rod 16. The lower end of the member 41 has threaded connection through use of a box-pin fitting 43 with the kelly bar 13. The member 41 is hollow so as to provide a passage 44 leading upward from the lower end thereof to a radial port 45 which communicates with the outer face of an enlargement or collar 46 formed on the body 41 intermediate the ends thereof. The mud joint 12 also comprises a shell 47 molded in the general form of a sleeve to fit around the hollow body 41 and having an annular drilling fluid passage 48 in opposing relation to the enlargement 46, this passage 48 having a radial inlet port 49 which communicates with a goose neck fitting 50 by which a rotary hose may be connected to the passage 48 for delivery thereto of a drilling fluid which may be rotary mud. The shell 47 has chambers 51 and 52 formed thereon by walls 53 which extend upward so as to form necks 54 having flanges 55 positioned so as to receive flanges 56 disposed at the lower ends of the tubular members 37 and being secured thereto by means of screws 57. The shell 47 has an inlet port 62 communicating with the passage 60 and an outlet port 63 communicating with the passage 61.

At the upper and lower ends thereof, the shell 47 is provided with upwardly and downwardly projecting frames 64 to carry bearing cases 65 which enclose roller bearings 66 by which the shell 47 is supported for coaxial rotation on the hollow body 41, thereby relieving the packing means 59 from undue lateral strains. The roller bearing means 66 are spaced from the enlargement 46 by sleeves 67 which extend from the shoulders at the ends of the enlargement 46 through the packing means 59 to engage the inner bearing races 68 of the bearing means 66, threaded sleeves 69 being applied to the outer ends of the races 68 to hold them in place.

The upper end of the hub 21 which projects upward from the lower end wall 18 has an annular recess 70 from which an oil passage 71 extends downward through the hub 21 and to the lower face of the end wall 18 so as to connect through a fitting 72 with a conduit 73 which is preferably of flexible character. Lubrication of the bearing 22 is accomplished through use of oil circulation passages 74 which extend radially inward from the vertical portion of the passage 71 below the annular recess 70. The piston 15 is provided with a downwardly projecting plug 75 which enters and closes the recess 70 as the piston 15 approaches the upper end of the hub 21.

The space 76 above the piston 15 is also filled with oil in the ordinary practice of the invention, and as the piston 75 moves down from a raised position, the oil which is released through the passage 71 is conducted into the upper space or chamber 76 of the cylinder through the conduct 73, a control valve 77, a flexible conduit 78, a fitting 79, which is connected to the flange portion of the lower end wall 18, and an oil transfer pipe 80 which passes up through the chamber 35 so as to connect through a welded hollow insert 81 with a vertical opening 82 which communicates with the interior of a cap 83 secured by bolts to the upper end of the cylinder 10.

In the operation of the rotary swivel the cylinder 10 is lowered relative to the piston 15 so that oil will be displaced from the upper chamber 76 to the lower chamber 19. When the piston 15 is in raised position the valve 77 may be closed so as to confine the body of oil in the lower chamber 19. The swivel may be then lifted so that the weight of the drilling string will be carried by the rod 16 and the piston 15 which rests on the body of oil in the chamber 19. At the time the drilling fluid may be fed under pressure through the rotary hose to the annular passage 48 of the shell 47 so that it will then pass through the ports 45 and the opening 44 of the tubular member 41 into the upper end of the string of drill pipe. An inlet 85 is connected to the water inlet port 62 so that water will then flow through the passage 60 into the first chamber 51 of the mud joint 12. This water will then pass up through the right hand tube 37 into the chamber 35 to cool the wall of the cylinder 14 and the thrust bearing means therein. From the chamber 35 the water will flow out through the left hand tubular member 37 into the second chamber 52 of the mud joint and will then pass through the annular passage 61 to the outlet port 63 to which a water discharge line 86 may be connected. The tubular members 37 have, in addition to their function of connecting the chambers 35, 51, and 52 into a single circulating system, the function of associating the rotary swivel and the mud joint 12 so that they will not have relative rotation but merely relative axial movement as the piston 15 and the rod 16 move relative to the cylinder 14.

An important feature of the invention is the provision of means for cooling the packing means 59, so that it will not become overheated, thereby greatly increasing the useful life of the packing to an extent shown by tests to be substantially three times the life of the packing where it is employed without the cooling means disclosed. This cooling means comprises chambers 90, individually identified as 90a and 90b, formed within the upper and lower wash-pipes or sleeves 67 adjacent the upper and lower packing means

59, to receive a flow of a cooling medium, such as water from the passages 60 and 61.

These chambers 90a and 90b may be formed by providing annular depressions 91 and 92 in either the interior faces of the sleeves 67 or in the external wall of the cylindrical body 41, but in the present practice of the invention I have shown both of the depressions or shallow depressions in use, whereby an increased width of chamber is obtained. The cooling fluid may be fed through the chambers 90a and 90b in the following manner. The packing means 59 is provided with an annular spacer 93, herein shown as a lantern, intermediate the ends of the packing means, and providing passage means 94 extending from the inner to the outer face of the spacer 93. Packing material of suitable character, for example, rings 96, is preferably disposed both above and below the spacer. Each sleeve 67 has openings 97 therein to connect the associated chamber 90 with the adjacent passage 95, and the walls 88 of the shell 47, surrounding the packing means 59, are provided with inlet and outlet openings 98 and 99 to connect the passages 95 of the upper and lower spacers 93 respectively with the water passages 60 and 61. In the arrangement shown, an effective cooling of the packings is obtained. The water in the chambers 90 takes heat from the sleeves 67 constituting the inner walls of the packing chambers. The water which flows through the passages 95 also absorbs heat from the packing, and the surrounding walls 88 of the packing chambers transfer heat from the packing to the water flowing in the respective upper and lower passages 60 and 61.

I claim as my invention:

1. In a rotary swivel and mud joint assembly of the character described, the combination of: a swivel body for connection to a suspension means, said body having thrust bearing means therein and a passage for circulation of a cooling medium in heat exchanging relation to said thrust bearing means; a suspension member extending down from said thrust bearing means for connection to the upper end of string of drill pipes; a mud joint connected to the upper portion of said string of drill pipes, said mud joint having a shell with walls forming a passage for circulation of a cooling medium; conduit means connecting said passages of said swivel body and said mud joint, said conduit means being so formed as to permit limited axial movement of said swivel body and said mud joint, and thereby forming a continuous passage including said passage of said swivel body and said passage of said mud joint; and means for circulating a cooling medium through the continuous passage thus formed.

2. In a rotary swivel and mud joint assembly of the character described, the combination of: a swivel body for connection to a travelling block in a derrick, said body having thrust bearing means therein and having a chamber for circulation of a cooling medium in heat exchanging relation to said thrust bearing means, said chamber having a downwardly faced opening; a suspension member extending down from said thrust bearing means for connection to the upper end of a string of drill pipes; a mud joint connected to the upper portion of said string of drill pipes, said mud joint having walls forming a passage for circulation of said cooling medium, said passage having an upwardly faced opening; a tubular member connecting said

downwardly faced opening and said upwardly faced opening, said tubular member being slid-able in at least one of said openings during relative axial movement of said swivel body and said mud joint, and connecting said chamber and said passage so as to form a continuous passage for circulation of said cooling medium; and means for circulating a cooling medium through said continuous passage.

3. In a rotary swivel and mud joint assembly of the character described, the combination of: a swivel body for connection to a travelling block in a derrick, said body having thrust bearing means therein and having a chamber for circulation of a cooling medium in heat exchanging relation to said thrust bearing means, said chamber having a downwardly faced opening; a suspension member extending down from said thrust bearing means for connection to the upper end of a string of drill pipes; a mud joint for connection to the upper portion of said string of drill pipes, said mud joint having walls forming a passage for circulation of said cooling medium, said passage having an outer opening; a tubular member connecting said downwardly faced opening and said outer opening, said tubular member being slid-able in said downwardly faced opening during relative axial movement of said swivel body and said mud joint, and connecting said chamber and said passage so as to form a continuous passage for circulation of said cooling medium; means for sealing around said tubular member where it slides in said downwardly faced opening; and means for circulating a cooling medium through said continuous passage.

4. In a rotary swivel and mud joint assembly of the character described, the combination of: a swivel body for connection to a suspension means, said body having thrust bearing means therein and a passage for circulation of a cooling medium in heat exchanging relation to said thrust bearing means; a suspension member extending down from said thrust bearing means for connection to the upper end of a string of drill pipes; a mud joint connected to the upper portion of said string of drill pipes, said mud joint having a shell with walls forming a first chamber and a second chamber for a cooling medium; conduit means connecting said first chamber with one part of said passage; conduit means connecting said second chamber with another part of said passage, said conduit means thereby forming a continuous passage from said first chamber through said passage to said second chamber; and means for delivering a cooling medium to said first chamber and releasing said cooling medium from said second chamber.

5. In a rotary swivel and mud joint assembly of the character described, the combination of: a swivel body for connection to a travelling block in a derrick, said body having a passage for a cooling medium, said passage having spaced downwardly faced openings; a thrust bearing means in said swivel body having a suspension member extending downwardly therefrom for connection to the upper end of a string of drill pipes; a mud joint connected to the upper portion of said string of drill pipes, said mud joint having walls forming a first chamber with an upwardly faced opening and a second chamber with an upwardly faced opening; a conduit connecting said opening of said first chamber with one of said downwardly faced openings of said swivel body; a conduit connecting said opening of said second chamber to the other of said

downwardly faced openings of said swivel body, each of said conduits being in slidable relation to at least one of said openings which it connects; and means for delivering a cooling medium to said first chamber and releasing the same from said second chamber.

6. In a rotary swivel and mud joint assembly of the character described, the combination of: a swivel body for connection to a travelling block of a derrick, said body having a passage for a cooling medium, said passage having spaced downwardly faced openings; a thrust bearing means in said swivel body having a suspension member extending downwardly therefrom for connection to the upper end of a string of drill pipes; a mud joint connected to the upper portion of said string of drill pipes, said mud joint having walls forming a first chamber with an upwardly faced opening and a second chamber with an upwardly faced opening; a conduit connecting said opening of said first chamber with one of said downwardly faced openings of said swivel body; a conduit connecting said opening of said second chamber to the other of said downwardly faced openings of said swivel body, each of said conduits being in slidable relation to the downwardly faced opening to which it connects and being rigidly secured to said mud joint; and means for delivering a cooling medium to said first chamber and releasing the same from said second chamber.

7. In a rotary swivel and mud joint assembly of the character described, the combination of: a swivel body for connection to a travelling block of a derrick, said body having a passage for a cooling medium, said passage having spaced downwardly faced openings; a thrust bearing means in said swivel body having a suspension member extending downwardly therefrom; a mud joint connecting the lower end of said suspension member to the upper end of said drilling string, said mud joint comprising a tubular body having its upper end connected to said suspension member and its lower end connected to said drilling string and having lateral ports, a swivel shell on said tubular body having a drilling fluid passage disposed for connection to said ports of said tubular body, carrying packing means above and below said ports, and having a first chamber and a second chamber in heat exchanging relation to said packing means, each of said chambers having an outer opening; a conduit connecting said opening of said first chamber with one of said downwardly faced openings of said swivel body; a conduit connecting said opening of said second chamber to the other of said downwardly faced openings of said swivel body, each of said conduits being in slidable relation to the downwardly faced opening to which it connects and being rigidly secured to said mud joint; and means for delivering a cooling medium to said first chamber and releasing the same from said second chamber.

8. In a mud joint for connection to the upper end of a string of drill pipes, the combination of: a tubular body having means at its lower end for connecting it to the upper end of said string of drill pipes, an enlargement disposed between the ends thereof and a lateral port connecting the external face of said enlargement with the interior of said tubular body; a shell rotatable on said tubular body, having a drilling fluid passage positioned so as to communicate with said port, and having passage means for a cooling medium above and below said drilling fluid pas-

sage; bearing members at the ends of said shell to support said shell for rotation on said tubular body, said bearing members having parts engaging the ends of said enlargement whereby the axial position of said bearings and said shell on said tubular body is determined; and upper and lower packing means carried between said shell and said tubular body above and below said port.

9. In a mud joint for connection to the upper end of a string of drill pipes, the combination of: a tubular body having means at its lower end for connecting it to the upper end of said string of drill pipes, an enlargement disposed between the ends thereof, and a lateral port connecting the external face of said enlargement with the interior of said tubular body; a shell rotatable on said tubular body, having a drilling fluid passage positioned so as to communicate with said port, and having passage means for a cooling medium above and below said drilling fluid passage; bearing members at the ends of said shell to support said shell for rotation on said tubular body, said bearing members having parts engaging the ends of said enlargement whereby the axial position of said bearings and said shell on said tubular body is determined; upper and lower packing means carried between said shell and said tubular body above and below said port and adjacent said cooling fluid passages; and walls rotating with said tubular body and forming adjacent said packing means chambers to receive a cooling medium, there being means to supply a cooling medium to said chambers.

10. In a mud joint for connection to the upper end of a string of drill pipes, the combination of: a tubular body having means at an end thereof to connect it to a string of drill pipes, said body having a lateral port intermediate its ends; a shell rotatable on said tubular body, having passage means to communicate with said port, said shell also having wall forming packing chambers around said tubular body above and below said port; packing means in said packing chambers; and thin cylindric walls mounted on and rotating with said tubular body and forming cooling chambers adjacent the inner limits of said packing chambers, said cooling chambers having means to supply them with a cooling medium.

11. In a mud joint for connection to the upper end of a string of drill pipes, the combination of: a tubular body having means at an end thereof to connect it to a string of drill pipes, said body having a lateral port intermediate its ends; a shell rotatable on said tubular body, having passage means to communicate with said port, said shell also having wall forming packing chambers around said tubular body above and below said port and external cooling chambers around said packing chambers; packing means in said packing chambers; and cylindric walls secured upon the surface of and rotating with said tubular body and forming internal cooling chambers adjacent the inner limits of said packing chambers, said cooling chambers having means to supply them with a cooling medium.

12. In a mud joint for connection to the upper end of a string of drill pipes, the combination of: a tubular body having means at an end thereof to connect it to a string of drill pipes, said body having a lateral port intermediate its ends; a shell rotatable on said tubular body, having passage means to communicate with said port, said shell also having wall forming packing chambers around said tubular body above and below said port and external cooling chambers around said

packing chambers; packing means in said packing chambers; walls rotating with said tubular body and forming internal cooling chambers adjacent the inner limits of said packing chambers; means to supply a cooling medium to said external cooling chambers; and means connecting said external and said internal cooling chambers so as to convey said cooling medium between said external and said internal cooling chambers.

13. In a rotary swivel and mud joint assembly of the character described, the combination of: a swivel for connection to a suspension means, said swivel having thrust bearing means therein and a passage for circulation of a cooling medium in heat exchanging relation to said thrust bearing means; a suspension member extending down from said swivel for connection to the upper end of a string of drill pipes; a mud joint connected to the upper portion of said drilling strings, said mud joint having a shell with walls forming a passage for circulation of a cooling medium; conduit means connecting said passages of said swivel and said mud joint, said conduit means being so formed as to permit limited axial movement of said swivel and said mud joint, and thereby forming a continuous passage including said passage of said swivel and said passage of

said mud joint; and means for circulating a cooling medium through the continuous passage thus formed.

14. In a rotary swivel and mud joint assembly 5 of the character described, the combination of: a swivel for connection to a suspension means, said swivel having thrust bearing means therein and a passage for circulation of a cooling medium in heat exchanging relation to said thrust bearing means; a suspension member extending down from said swivel for connection to the upper end of a string of drill pipes and cooperating with said drill pipe so as to form a continuous drilling string; a mud joint connected to the upper portion of said drilling string, said mud joint having a shell with walls forming a passage for circulation of a cooling medium; conduit means connecting said passages of said swivel and said mud joint, said conduit means being so formed as to permit limited axial movement of said swivel and said mud joint, and thereby forming a continuous passage including said passage of said mud joint; and means for circulating a cooling medium through the continuous passage thus formed.

GUGLIELMO R. TREMOLADA.
